UNITED STATES PATENT OFFICE.

PAUL E. BRENEMAN, OF DETROIT, MICHIGAN, ASSIGNOR TO C. R. WILSON BODY COMPANY, OF DETROIT, MICHIGAN, A CORPORATION OF MICHIGAN.

METAL BODY FOR VEHICLES.

Application filed July 17, 1920. Serial No. 396,886.

To all whom it may concern:

Be it known that I, PAUL E. BRENEMAN, a citizen of the United States of America, residing at Detroit, in the county of Wayne and State of Michigan, have invented certain new and useful Improvements in Metal Bodies for Vehicles, of which the following is a specification, reference being had therein to the accompanying drawings.

10 The invention relates to metallic bodies for vehicles of the type in which the structural frame, as well as the panels of the body, is formed of metal. It is the object of the invention to simplify the construction and particularly to reduce the labor in assembling and the welding or otherwise uniting of the various elements. It is a further object to build the body in a plurality of units which are capable of being assembled 15 with each other after the enameling step. With these objects in view the invention consists in the construction as hereinafter set forth.

In the drawings:

25 Figure 1 is a side elevation of the body; Figure 2 is a cross-section on line 2—2 of Figure 1;

Figure 3 is a similar cross-section on line 3—3 of Figure 1;

30 Figure 4 is a longitudinal section on line 4—4 of Figure 2 showing the manner of uniting the units;

Figure 5 is a cross-sectional view on line 5—5 of Figure 2.

35 In the construction of metallic bodies it is the usual practice to form the elements thereof of sheet metal stampings, which are then united to each other, and to the supporting frame by spot-welding or equivalent means.

40 The labor of assembling and uniting these elements is a large factor in the cost of the structure and therefore, reduction in a number of elements and joints or seams to be welded will correspondingly reduce the 45 total cost. With the present invention I have devised a peculiar design in which a number of parts is reduced and where a few integral stampings take the place of a larger number in structures as heretofore designed.

50 Also by forming the body in units, which may be united after the enameling process, the bodies may be more conveniently

shipped and can be quickly assembled for delivery.

In detail, my improved construction comprises three units, viz, a tonneau unit A, a center and front seat unit B, and a cowl unit C. Each of these units is formed with a floor and sill member D having a channel portion E extending longitudinally above the chassis sills, a floor portion F extending outward therefrom and a flange G extending inward in a lower plane and constituting a support for the floor boards H. It is necessary in each of the units to form a threshold 55 for the door opening and in each of the units A and B a seat support. These are formed integral with the member D and, as shown in Figure 2, the floor portion F has the upturned portion I terminating in 60 the outwardly-extending flange J, which underlaps an inwardly-extending flange K on the outer panel L of the body. Also, the floor portion F in a different plane, as indicated in Figure 3, has the upwardly-extending 65 portion I' of greater height, with the laterally-extending seat-supporting portion J' terminating in a flange M, which is united to the outer panel L. Thus in one integral 70 stamping is formed the floor F, the sill portion E, the threshold and the seat support. 75

The lower edge of the outer panel L of the body is secured to the member D by an inturned channel member N. This is formed with its web portion N' at an angle corresponding to that of the outer panel, the parallel portions N² and N³, the former being united to the floor portion F. The panel L is also provided with an inturned flange L', which is united with the portion N². 80

85 The construction of the cowl unit C is the same as the units A and B, with the exception that the threshold portion is integral with a portion O, forming the toe board, both being integral with the sill portion D. The outer panels of each of the units are formed of suitable stampings united to each other and to the elements already described, so as to make a rigid structure. Thus the center unit B is provided with the front seat back P and with a door post portion Q, while the units A and C are each provided with door post 90 portions adjacent to the door openings. 100

The units constructed as described are adapted to abut against each other. To rigidly unite them, there are provided members R, preferably castings, which bridge the joint between the units and are fashioned to engage the channel member N and to extend inward therefrom to the sill member E. The portions of the unit overlapping this member R may be secured there-
 10 to by rivets S, while within the channel of the sill member E there is placed a reinforcing plate P' through which certain of the rivets pass. As this riveting can be performed without injury to the enamel finish, it is obvious that the units may be completed, including the enamel and the enameling, and then separately shipped to the point for final assembly.

What I claim as my invention is:

20 1. A metallic vehicle body comprising a plurality of units arranged in longitudinal series, each unit extending the full width of the body and having a sill portion, and means for uniting the sill portions of said units to rigidly attach the same independent of the chassis frame, forming composite sills extending substantially the full length of the body.

25 2. A metallic vehicle body comprising a plurality of units arranged in longitudinal series and abutting against each other, each unit extending the complete cross-section of the body and including a supporting sill portion, and a member bridging the joint between units in the sill portions thereof and rigidly uniting the same, and means rigidly securing said bridging member to each of the units which it joins.

30 3. In a metallic vehicle body, the combination with the outer panel having an inturned flange at the threshold of the door opening, and a member forming a sill for resting upon the sill of the chassis frame having an outwardly-extending floor portion and upturned portion, and an out-turned flange for uniting with the inturned flange of said threshold.

35 4. In a metallic vehicle body, the combination with the outer panel having an in-turned flange at the door opening therein, of a member having a sill portion arranged above the sill of the chassis frame, an outwardly extending floor portion, an upturned portion and an out-turned flange uniting with the inturned flange of said outer panel.

40 5. In a metallic vehicle body, the combination with the outer panel having an in-turned flange at the lower edge thereof and an inturned flange surrounding the door opening, of a channel-shaped member having its web portion conforming to the angle of said outer panel and lying adjacent thereto and its flange portions extending inward parallel to each other, the lower flange being attached to the lower flange of said

outer panel, and a member having a channel-shaped sill portion arranged above the sill of the chassis frame, an outwardly extending floor portion uniting with the upper flange of said first-mentioned channel member, an upturned portion forming an inner panel of the body, and an outturned flange uniting with said inturned flange surrounding the door opening.

6. In a metallic vehicle body, the combination with the outer panel, having an in-turned flange at its lower edge, of a channel member having its web portion conforming to the outer panel and provided with inwardly-extending parallel flanges, the lower flange being united to the inturned flange of said panel member, and a member having a channel sill portion arranged above the chassis sill, an outwardly-extending floor portion supported upon said first-mentioned channel member, an upturned portion forming an inner panel for the body with an out-turned flanged portion, said upturned portion and flanged portion extending to form both the threshold of the door opening and the seat support.

7. A metallic vehicle body comprising a plurality of units arranged in longitudinal series and abutting, each unit comprising an outer panel and an integral stamping forming an inner panel, a threshold, a floor portion, and a sill portion extending above the chassis sill, and a member for connecting said units bridging the joint therebetween and attached to the floor and sill portion of said units.

8. In a metallic vehicle body, a member having a channel sill portion arranged above the chassis sill, an outwardly extending floor portion, and an upturned portion forming an inner panel for the body and outwardly flanged to form a seat support.

9. A metallic vehicle body comprising a plurality of units arranged in longitudinal series and abutting against each other, each unit extending the complete cross section of the body and including a supporting sill portion, and a member bridging the joint between units in the sill portions thereof and rigidly uniting said units, said bridging member extending substantially the full width of the sills.

10. A metallic vehicle body comprising a plurality of units arranged in longitudinal series and abutting, each unit comprising an outer panel, a sill portion and a channel member connecting said panel and sill portion, and a member for connecting said units, bridging the joint therebetween, said member being arranged beneath the sill portions of the connected panels and fitting within said channel member.

11. In a metallic vehicle body, the combination with a side panel of said body, of a sheet metal member having a seat support.

ing portion secured to said panel, an intermediate floor portion, and an inner portion forming a floor board support.

12. A metallic vehicle body comprising a plurality of units arranged in longitudinal series and abutting against each other, each unit including a supporting sill portion having a relatively depressed inner portion

and a bridging member connecting said units disposed beneath the joints of the sills 10 thereof and formed with a depressed portion engaging beneath said depressed inner portions of said units.

In testimony whereof I affix my signature.

PAUL E. BRENEMAN.
